(57) **CLAIM**

The ornamental design of a pet treat, as shown and described.

DESCRIPTION

FIG. 1 is a top plan view of a first embodiment of a pet treat; FIG. 2 is a bottom plan view thereof;

FIG. 3 is a front elevation view thereof;

FIG. 4 is rear elevation view thereof;

FIG. 5 is a right side elevation view thereof;

FIG. 6 is a left side elevation view thereof;

FIG. 7 is a top plan view of a second embodiment of a pet treat;

FIG. 8 is a bottom plan view thereof;

FIG. 9 is a front elevation view thereof;

FIG. 10 is rear elevation view thereof;

FIG. 11 is a right side elevation view thereof;

FIG. 12 is a left side elevation view thereof;

FIG. 13 is a top plan view of a third embodiment of a pet treat;

FIG. 14 is a bottom plan view thereof;

FIG. 15 is a front elevation view thereof;

FIG. 16 is rear elevation view thereof;

FIG. 17 is a right side elevation view thereof;

FIG. 18 is a left side elevation view thereof;

FIG. 19 is a top plan view of a fourth embodiment of a pet treat;

FIG. 20 is a bottom plan view thereof;

FIG. 21 is a front elevation view thereof;

FIG. 22 is rear elevation view thereof;

FIG. 23 is a right side elevation view thereof;

FIG. 24 is a left side elevation view thereof;

FIG. 25 is a top plan view of a fifth embodiment of a pet treat;

FIG. 26 is a bottom plan view thereof;

FIG. 27 is a front elevation view thereof;

FIG. 28 is rear elevation view thereof;

FIG. 29 is a right side elevation view thereof;

FIG. 30 is a left side elevation view thereof;

FIG. 31 is a top plan view of a sixth embodiment of a pet treat;

FIG. 32 is a bottom plan view thereof;

(Continued)

FIG. 33 is a front elevation view thereof;
 FIG. 34 is rear elevation view thereof;
 FIG. 35 is a right side elevation view thereof;
 FIG. 36 is a left side elevation view thereof;
 FIG. 37 is a top plan view of a seventh embodiment of a pet treat;
 FIG. 38 is a bottom plan view thereof;
 FIG. 39 is a front elevation view thereof;
 FIG. 40 is rear elevation view thereof;
 FIG. 41 is a right side elevation view thereof;
 FIG. 42 is a left side elevation view thereof;
 FIG. 43 is a top plan view of an eighth embodiment of a pet treat;
 FIG. 44 is a bottom plan view thereof;
 FIG. 45 is a front elevation view thereof;
 FIG. 46 is rear elevation view thereof;
 FIG. 47 is a right side elevation view thereof;
 FIG. 48 is a left side elevation view thereof;
 FIG. 49 is a top plan view of a ninth embodiment of a pet treat;
 FIG. 50 is a bottom plan view thereof;
 FIG. 51 is a front elevation view thereof;
 FIG. 52 is rear elevation view thereof;
 FIG. 53 is a right side elevation view thereof;
 FIG. 54 is a left side elevation view thereof;
 FIG. 55 is a top plan view of a tenth embodiment of a pet treat;
 FIG. 56 is a bottom plan view thereof;
 FIG. 57 is a front elevation view thereof;
 FIG. 58 is rear elevation view thereof;
 FIG. 59 is a right side elevation view thereof;
 FIG. 60 is a left side elevation view thereof;
 FIG. 61 is a top plan view of an eleventh embodiment of a pet treat;
 FIG. 62 is a bottom plan view thereof;
 FIG. 63 is a front elevation view thereof;
 FIG. 64 is rear elevation view thereof;
 FIG. 65 is a right side elevation view thereof;
 FIG. 66 is a left side elevation view thereof;
 FIG. 67 is a top plan view of a twelfth embodiment of a pet treat;
 FIG. 68 is a bottom plan view thereof;
 FIG. 69 is a front elevation view thereof;
 FIG. 70 is rear elevation view thereof;

FIG. 71 is a right side elevation view thereof; and,
 FIG. 72 is a left side elevation view thereof.
 The broken lines shown in FIGS. 1-72 illustrate portions of the pet treat that form no part of the claimed design.
 The differing shades of grey in FIGS. 1-72 represent a contrasting appearance.
